UNITED STATES PATENT OFFICE.

THEODORE VARNEY, OF PITTSBURG, PENNSYLVANIA, ASSIGNOR TO WESTINGHOUSE ELECTRIC & MANUFACTURING COMPANY, A CORPORATION OF PENNSYLVANIA.

INSULATOR AND SUPPORT FOR ELECTRIC LINES.

No. 861,063.

Specification of Letters Patent.

Patented July 23, 1907.

Application filed June 4, 1906. Serial No. 320,137.

To all whom it may concern:

Be it known that I, THEODORE VARNEY, a citizen of the United States, and a resident of Pittsburg, in the county of Allegheny and State of Pennsylvania, have 5 invented a new and useful Improvement in Insulators and Supports for Electric Lines, of which the following is a specification.

My invention relates to insulators and supports for electric lines and it has for its object to provide a device of the aforesaid character that shall be simple and durable in construction and that shall be specially adapted for use with relatively heavy electric conductors which are supported at infrequent intervals.

When electric lines, as frequently constructed in the 15 prior art, for various purposes, have comprised small low voltage conductors, the line insulators were subjected to slight strains, particularly when the poles were placed near together and when nothing was supported from the insulators except the weight of the conductor 20 attached to them. On the other hand, the modern design and construction of such electric lines as are adapted for high voltages and high speed trolleys, require insulators of an improved construction in order that they may withstand the strains to which they are 25 subjected.

According to my present invention, I provide an insulating support which is specially adapted for use with a catenary form of line construction which is supported at widely separated points, although it is of course not 30 restricted to such use.

The single figure of the accompanying drawing is a side elevation of an insulating support constructed in accordance with my invention.

The insulator illustrated in the drawing comprises 35 a head 1 of hard insulating material, a pin 2 on which the head is mounted, a supporting bracket 3 and a clamping device 4. The supporting bracket 3 is adapted to engage a pair of angle irons 5 and 6 of which a suitable bridge structure may be comprised and is fastened 40 thereto by detachable clamping members 7 and bolts 8. A semi-cylindrical ledge 9 is formed substantially in the middle of the bracket into which the lower extremity of the pin 2 is seated, the pin 2 being held in position by means of U-shaped clamping bolts 10. The ends 45 of the bolts pass through holes 11 in the bracket 3 and are engaged by nuts which are screw-threaded onto their ends. The pin 2 may comprise a rod or a tube of iron or other suitable material and is of sufficient length to project a considerable distance above the 50 bracket.

The insulator head 1, to which a conductor may be attached, is provided with a bell flange or petticoat 12 that decreases the electrical leakage between the conductor and the grounded bracket 3. The end of the

pin 2 enters for a considerable distance and is cemented 55 into the head 1 in order to increase the mechanical strength of the assembled structure. The upper end of the insulating head 1 is provided with a groove 13 which is engaged by a conductor 14, and its outer surface is tapered inwardly as it approaches the bell flange 60 or petticoat 12.

The conductor 14 is held in position by means of the clamping device 4 that comprises a collar clamp 15 having complementary halves which are adapted to engage the tapered surface of the head 1 and clamping 65 ears 16 and 17 that are pivotally attached to the collar clamp 15 at diametrically opposite points. The clamping ears 16 and 17 are provided with a groove 18, in which conductor 14 may lie, and suitable holes 19 through which U-shaped clamping bolts 20 may pass. 70 The inner surface of the insulating head, which receives the end of the pin 2, may preferably be corrugated so that cement or other suitable substance will form a more permanent joint when it is hardened.

The arrangement of parts hereinbefore described is 75 of special advantage since the insulator proper is relieved of substantially all except compressional strains. This fact is obvious from the relative position on opposite sides of the insulator head 1 of the pin 2 and the collar clamp 15 which may readily be contrasted with 80 the arrangement of the prior art in which strains have usually been applied to the insulator at a point considerably above the end of the supporting pin.

Although I have illustrated and described a specific arrangement, I desire that only such limitations be 85 imposed as are indicated in the appended claims.

I claim as my invention:

1. In an electric line construction, the combination with a head of hard insulating material, a supporting pin therefor and a collar clamp attached to the head, of clamping 90 ears that are pivotally attached to the collar and a line conductor which is engaged by the clamping ears and rests upon the top of the insulating head.

2. An insulating support for electric lines comprising a head having a bell flange or petticoat of insulating material, a pin fitted into the head, a collar clamp engaging its outer surface adjacent to the bell flange or petticoat and clamping ears that are pivotally attached to the collar clamp. 95

3. A supporting insulator for electric lines that comprises a bracket, a pin, an insulator having a hollow head fitted onto the pin, a bell flange or petticoat, a groove in the end of the insulating body member and a collar clamp attached thereto which surrounds the end of the pin and is supported therefrom by the insulator and clamping ears 100 that are pivotally attached to the collar. 105

4. An insulator for electric lines comprising a metal frame, a tubular pin extending upwardly therefrom, a petticoat insulator mounted thereon and a collar attached to the insulator and clamping ears that are pivotally attached to the collar. 110

5. An insulator for electric lines that comprises a bracket, a semi-cylindrical ledge therein, a tubular pin

seated in the ledge, U-shaped clamping bolts which hold the pin in position, a petticoat insulator mounted on the pin, a collar attached to the insulator and clamping ears pivotally attached to the collar.

5. An insulator for electric lines comprising a tubular pin, a petticoat insulator, a collar mounted thereon and clamping ears pivotally attached to the collar.

7. An insulator for electric lines comprising a metal frame, a tubular pin extending upwardly therefrom, a 10 molded insulator having a grooved head and mounted on

said pin, a bell shaped member integral with the insulator, a collar attached to the head and a pair of clamping ears pivotally attached to opposite points in the collar.

In testimony whereof, I have hereunto subscribed my name this 31st day of May, 1906.

THEODORE VARNEY.
